DRILLING MECHANISM

Frank Miller, East Orange, N. J., assignor to
Ingersoll-Rand Company, New York, N. Y., a
corporation of New Jersey

Application March 23, 1940, Serial No. 325,485

2 Claims. (Cl. 255—4)

This invention relates to a rotary drilling apparatus, and more particularly, it relates to a drilling apparatus of the type employed in drilling wells, and the like, which form removable earthen cores by cutting annular channels thereabout.

In the operation of such devices it is desirable to constantly present a highly abrasive cutting surface to the work and to this end shot is constantly introduced into the hole while it is being drilled. Heretofore, the means employed for introducing the shot has been complicated and in the nature of an accessory that had to be applied to the drill and used in such a manner that it did not pass through or interfere with the drill operating mechanism.

It is, accordingly, an object of the present invention to provide a shot feeding mechanism which is integral with the drilling apparatus.

Another object is to provide a drill shot feeding mechanism which extends through moving parts of the drill.

It is a further object to provide a simple, compact and efficient drill shot feeding mechanism.

These and other objects will be in part obvious and in part pointed out in the following specification of which the drawing forms a part and in which similar reference numerals refer to similar parts.

Figure 1 is a view in section of a drilling apparatus constructed and arranged in accordance with the principles of the present invention, and

Figure 2 is a transverse view taken along line 2—2 of Fig. 1.

With reference to Fig. 1, a rotary drilling apparatus constructed in accordance with the principles of the present invention is generally indicated at 1 and consists of a drill or cutting tool 3 having a series of slots 5 (two of which are shown in dotted lines in Fig. 1) to define the cutting teeth in the tool 3. Upon rotation of the tool 3 the cutting teeth cut an annular kerf 7 in the earth formation severing the core 9 therefrom in order that it may be removed to form a hole defined by the wall 11. Within the tool 3 is a transverse plate 13 rigidly secured thereto and below the transverse plate is a baffle plate 15 held in position by the bolts 17 extending through both of the plates.

The transverse plate 13 is provided with a port 19 opening into the hollow shaft, or stem, 21. The plate 13 and shaft 21 are fastened together by the flange coupling 23 which is secured on the transverse plate 13 by bolts 25 and is provided with threads 27 to engage com-

plementary threads provided on the shaft 21. Likewise, the upper end of the shaft 21 has threads 29 by means of which the connector, or space piece, 31 may be secured thereto. The lower wall of the connector has a bore 33, the purpose of which will be explained hereinafter, and a larger bore 35 in its upper wall. A threaded flange 37 is bolted to the upper wall of the connector 31 and is adapted to be threadedly secured to the sleeve 39 formed on the driven gear 41 of a reduction gearing, generally indicated at 43. The reduction gearing 43 forms a part of the driving mechanism and is located within the base 45 on which rests the driving motor 47.

The entire driving mechanism consisting of the motor 47, the base 45 and the gearing 43 is enclosed in the casing 49. This casing is adapted to be raised or lowered in the hole being drilled by the stem 51 detachably secured by the studs 53 to the wall 55 which forms a part of the casing 49. The lower wall 57 of the casing 49 has a sleeve 59 through which passes the gear sleeve 39 and between which is placed the bushing 61. A bearing 63 rests on the upper surface of the sleeve 59 and supports the driven gear 41. It will be noted that the passage 65, through the gear sleeve 39, is actually aligned with the motor shaft 67 and that the motor shaft 67 extends from the motor, through the reduction gearing 43 and terminates within the passage 65.

The motor base 45 has two partitions 69 and 71 to support the follower gear shafts 73 and 75. The partition wall 69 has a central opening in which is placed the bushing 77, serving to guide the motor shaft 67 and, likewise, the wall 71 has the bushing 79. Between the walls 69 and 71 the driver gear 81 is keyed to the motor shaft 67 and drives the follower gears 83 and 85 which are fastened respectively to the gear shafts 73 and 75. Below wall 71 and within the internal driven gear 41 and arranged so as to intermesh therewith are the follower gears 87 and 89; the follower gear 87 being securely fastened to the shaft 73, and gear 89 to the shaft 75.

With this arrangement it is apparent that, when the motor 47 rotates the shaft 67, the driver gear 81 will also rotate and, since it is in mesh with the gears 83 and 85, these gears will rotate and also revolve their respective shafts. Revolution of shafts 73 and 75 will cause the gears 87 and 89 to move the driven gear 41 and thus, by means of sleeve 39, connector 31 and shaft 21 revolve the cutting tool 3.

As will be seen from Fig. 2, the shaft 67 is

tubular and, consequently, has a passage 91 extending through its entire length. Through this passage and spaced therefrom, is the shot feeding conduit, or tube, 93. This conduit is formed with an enlarged portion 95 designed to extend through an opening 97 centrally located in the upper wall 99 of the casing 49. In order that the conduit 93 may revolve with respect to the casing 49, which is held against rotation, the portion 95 is journaled in the bearing 101, resting on the upper wall 99 of the casing.

The portion 95 of the conduit 93 is arranged to receive the pipe 103 which forms a part of the shot supply means. A bushing 102, surrounding pipe 103 holds the packing 104 against the portion 95 of the conduit 93. The pipe 103 is connected by elbow 105 and pipe 107 to a valve 109 through which shot may be introduced into the pipe. Adjacent the valve 109 and interposed in the pipe 107 is a valve 111 through which water may be introduced if it is desired. The lower end of the conduit 93 extends into the shaft 21 and passes through the bore 33. A stuffing box, consisting of the bushing 113 and packing 115, rests in the recess 117 formed in the connector just above the bore 33. This stuffing box prevents any passage of material between bore 33 and the conduit 93. When the motor 47 is driving the tool 3, as previously explained, the speed of the motor will naturally be much greater than the speed of the drill and, by spacing the conduit 93 from the shaft 67, the conduit 93 may remain substantially stationary. Of course, if desired, the conduit 93 and pipe 103 may be one continuous pipe and then there would be no necessity for bearing 95, since conduit 93 would then always be stationary. If, however, conduit 93 should be rotated, due to the friction between the conduit 93 and the stuffing box, the speed of rotation of the two would only be equal to the speed of rotation of the drill which would not, in any way, hinder the passage of shot through the conduit 93.

When it is desired to employ the shot, it may be introduced through the valve 109 with or without water supplied through valve 111. The

shot introduced through the pipe 107 will fall by gravity through pipe 103 into the conduit 93 and, after leaving conduit 93, will pass through the shaft 21 and the port 19 to strike the baffle plate

5 15. The baffle plate 15 serves to deflect the shot from the core 9 and let it drop to the cutting tool formed on the drill 3 in order that the cutting teeth may be kept clean. In order to remove the cuttings it will be necessary to introduce water 10 with the shot so that the cuttings may be carried upwardly from the cutting teeth by the water through the space between the wall 11 and the cutting tool 3 and be deposited on the transverse plate 13.

15 20 This construction, therefore, lends itself to a simple but efficient method of introducing shot to the cutter tool of a rotary drill and, although a preferred embodiment of the invention has been illustrated and described, it is not to be limited save as defined in the appended claims.

I claim:

1. In a rotary drilling apparatus, a casing, a driving motor in the casing having a shaft, a series of reduction gears in the casing adapted to be driven by the motor, a sleeve on one of the reduction gears, a connector secured to the sleeve, a cutter element secured on the connector, a stuffing box in the connector, a tube extending through the motor and reduction gears and stuffing box terminating adjacent the cutter to supply shot thereto.

2. In a rotary drilling apparatus, a casing, a driving motor in the casing, a series of reduction gears in the casing, a shaft to enable the motor 35 to drive the gears, a sleeve on one of said gears extending through the casing, a bearing on the casing for the sleeve, a connector secured to the sleeve, a stuffing box in the connector, a hollow shaft secured on the connector, a rotary cutting tool on the shaft, a conduit extending through the motor shaft and terminating in the hollow shaft, and a pipe through the casing opening into the conduit to supply shot through the conduit to the rotary cutting tool.
